[57] CLAIM

The ornamental design for a handle for spoons, as shown and described.

DESCRIPTION

FIG. 1 is a perspective view of a handle for spoons showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing spoon bowl in FIGS. 1-5 and 7 are environmental only and form no part of the claimed design.

Further, the broken lines adjacent to the full line disclosure represent the boundary of the claimed design and forms no part thereof.
